(57) **CLAIM**

The ornamental design for a medical device electronic connector plug, as shown and described.

DESCRIPTION

FIG. 1 is a front elevation view of a medical device electronic connector plug according to a first embodiment of the invention.

FIG. 2 is a rear elevation view thereof.

FIG. 3 is a top plan view thereof.

FIG. 4 is a bottom plan view thereof.

FIG. 5 is a left side view thereof.

FIG. 6 is a right side view thereof.

FIG. 7 is a first perspective view thereof.

FIG. 8 is a second perspective view thereof.

FIG. 9 is an enlarged perspective view of a portion thereof.

FIG. 10 is another enlarged perspective view of a portion thereof.

FIG. 11 is another enlarged perspective view of a portion thereof; and,

FIG. 12 is another enlarged perspective view of a portion thereof.

The present embodiment includes a design for a plug portion of an electronic connector cable. The plug includes a center post surrounded by 17 pins, where the area surrounding the post and the pins is recessed.

The features shown in evenly broken lines do not form part of the claimed design. The dot-dash broken lines indicate boundaries to claimed areas of the design.
